UNITED STATES PATENT OFFICE.

EDGAR C. KAYE, OF CHICAGO, ILLINOIS.

PNEUMATIC SOLE FOR SHOES.

1,109,130.

specification of Letters Patent.

Patented Sept. 1, 1914.

Application filed October 13, 1913. Serial No. 794,899.

To all whom it may concern:

Be it known that I, EDGAR C. KAYE, a citizen of the United States, and a resident of the city of Chicago, county of Cook, and State of Illinois, have invented certain new and useful Improvements in Pneumatic Soles for Shoes, of which the following is a specification.

My invention relates to a pneumatic sole especially adapted for use upon athletic shoes, or adapted for arrangement upon ordinary shoes to facilitate walking, running or jumping.

The object of my invention is the production of a pneumatic sole in the form of an attachment, which may be readily and easily arranged in position, and as easily and quickly detached, and which will be of simple construction and efficient in use.

Other objects will appear hereinafter.

The invention consists in the combinations and arrangements of parts hereinafter described and claimed.

The invention will be best understood by reference to the accompanying drawings forming a part of this specification, and in which,

Figure 1 is a side elevation of a shoe equipped with a pneumatic sole embodying my invention, the latter and the sole portion of the shoe being shown in section, Fig. 2 is a top plan view of the pneumatic sole detached, Fig. 3 is a bottom plan view thereof, Fig. 4 is a perspective view of the peripheral frame of the body of the pneumatic sole, a portion thereof being shown in section, Fig. 5 is a perspective view of the inner or top plate of the pneumatic sole detached, Fig. 6 is a transverse section taken on substantially line $x-x$ of Fig. 2, and Fig. 7 is a transverse section taken on substantially line $y-y$ of Fig. 1.

The preferred form of construction as illustrated in the drawings comprises a rigid body consisting of a peripheral frame 1 of a form corresponding with that of the shoe sole upon which the same is designed to be attached. At the upper side of the frame 1 is provided a wall 2, countersunk in said frame and detachably secured in position by means of screws 3. The front end of the wall or plate 2 is additionally secured by means of a reinforcing plate 4 secured to the frame 1 by pins or rivets 5, the front end of the plate 2 being adapted to engage under the member 4 and be thus

securely held in position, notches 6 being provided at said end of said plate to accommodate the pins or rivets 5.

Arranged at the under side of the frame 1 is a flexible wall 7 having its peripheral portion secured to the frame 1 by means of pins or rivets 8. The wall 7 is of a flexible nature being formed preferably of leather, the same being normally held in an outwardly flexed or convex position by means of a flexible air bag 9 inserted in the frame 1 between the walls 2 and 7. The bag 9 is inflated through the medium of a tube 10 which is accessible through an opening 11 provided in the plate 2 which is normally closed by a screw plug 12. Said tube 10, after inflation of the bag 9 is bent upon itself and securely bound by an elastic band or cord to prevent leakage. By detachably securing the plate 2 in position in the event of the bag 9 becoming punctured or otherwise disabled, said plate may be readily and easily detached in order to permit of removal of said bag.

The pneumatic sole is detachably secured to the sole of the shoe by means of a headed pin or screw 13 which projects from the shoe sole, the inner end of said pin or screw being threaded into a nut or bushing 14 arranged in the shoe sole adjacent the front end thereof. The headed outer end of the pin or screw 13 is adapted to releasably engage a key hole slot 15 provided in the plate 2 adjacent the toe portion of the sole. The rearward end of the pneumatic sole is releasably locked to the shoe sole by means of a screw 16 which extends through the latter being threaded into the rearward portion of the frame 1, as clearly shown in Fig. 1. With this arrangement it will be seen that the pneumatic sole is detachably secured to the shoe, being adapted to be detached by simply removing the screw 16, it being clear, that upon removal of said screw or release of the rearward end of the pneumatic sole, the forward end of the same may be readily released by sliding the same forwardly until the head of the member 13 registers with the enlarged portion of the slot 15. The reverse operation is of course resorted to in attaching the pneumatic sole to the shoe.

A pneumatic sole of the construction set forth will lend elasticity and resiliency to the step and thereby facilitate walking, running or jumping as the case may be. In

order to prevent lateral rolling of the foot when the sole is in use, strips 17 preferably of leather, or other flexible material, are arranged at the opposite sides of the sole at 5 the under side thereof which serve to limit the amplitude of lateral rocking or rolling which will be permitted the sole when in use, said members 17 serving as stops in this connection.

10 While I have illustrated and described the preferred form of construction for carrying my invention into effect, this is capable of variation and modification without departing from the spirit of the invention. I, 15 therefore, do not wish to be limited to the precise details of construction set forth, but desire to avail myself of such variations and modifications as come within the scope of the appended claims.

20 Having described my invention what I claim as new and desire to secure by Letters Patent is:

1. The combination with a shoe, of a pneumatic sole therefor comprising a rigid hollow body open at its under side; a flexible convex outer wall at said open side of said body; a flexible air bag arranged within said body for normally holding said outer wall flexed outwardly; and means on said 25 outer wall at opposite sides thereof for preventing lateral rolling of said sole when in use, substantially as described.

2. The combination with a shoe, of a pneumatic sole therefor comprising a rigid hollow body open at its under side; a flexible convex outer wall at said open side of said body; a flexible air bag arranged within said body for normally holding said outer 35 wall flexed outwardly; and flexible strips on said outer wall at opposite sides thereof for preventing lateral rolling of the sole when in use, substantially as described.

3. The combination with a shoe, of a pneumatic sole therefor comprising a rigid peripheral frame; a rigid inner wall having its periphery secured to one side of said frame; a flexible outer wall having its periphery secured to the other side of said frame; and a flexible air bag arranged within said 45 frame between said inner and outer walls for normally holding said outer wall in outwardly flexed position, substantially as described.

4. The combination with a shoe, of a pneumatic sole therefor comprising a rigid comparatively shallow body open at its under side; a flexible convex outer wall at said open side of said body; a flexible air bag arranged within said body for normally 55

holding said outer wall flexed outwardly; 60 means for releasably securing said sole to the sole of said shoe, said means comprising a slot and pin connection between the toe portion of said sole body and the corresponding portion of the shoe sole; and a releasable connection between the opposite end portion of said sole body and the corresponding portion of the shoe sole, substantially as described.

5. The combination with a shoe, of a pneumatic sole therefor comprising a rigid comparatively shallow body open at its under side; a flexible convex outer wall at said open side of said body; a flexible air bag arranged within said body for normally holding said outer wall flexed outwardly; 70 means for releasably securing said sole to the sole of said shoe, said means comprising a headed pin projecting from the shoe sole adapted to releasably engage a key hole 75 slot provided in the toe portion of said sole body; and a screw for releasably locking the opposite end of said sole body to the shoe sole, substantially as described.

6. The combination with a shoe, of a pneumatic sole therefor comprising a rigid peripheral frame; a rigid inner wall having its periphery secured to one side of said frame; a flexible outer wall having its periphery secured to the other side of said frame; and a flexible air bag arranged within said 85 frame between said inner and outer walls for normally holding said outer wall in outwardly flexed position, said inner wall being releasably secured in position to permit of 90 access to said air bag, substantially as described.

7. The combination with a shoe, of a pneumatic sole therefor comprising a rigid body; a flexible convex wall secured to the under 100 side of said body; a flexible air bag arranged for normally holding said wall flexed outwardly; means for releasably securing said sole to the sole of said shoe, said means comprising a slot-and-pin connection between 105 one end of said sole body and the corresponding portion of the shoe sole; and a releasable connection between the opposite end portion of said sole body and the corresponding portion of the shoe sole, substantially 110 as described.

In testimony whereof I have signed my name to this specification in the presence of two subscribing witnesses.

EDGAR C. KAYE.
